UNITED STATES PATENT OFFICE.

EDWIN S. CARMAN, OF CLEVELAND, OHIO, ASSIGNOR TO THE OSBORN MANUFACTURING COMPANY, OF CLEVELAND, OHIO, A CORPORATION OF OHIO.

MECHANISM FOR MAKING MOLDS.

1,357,380.

Specification of Letters Patent. Patented Nov. 2, 1920.

Application filed November 15, 1913. Serial No. 801,127.

To all whom it may concern:

Be it known that I, EDWIN S. CARMAN, a citizen of the United States, and a resident of Cleveland, county of Cuyahoga, and State 5 of Ohio, have invented a new and useful Improvement in Mechanism for Making Molds, of which the following is a specification, the principle of the invention being herein explained and the best mode in which I have 10 contemplated applying that principle, so as to distinguish it from other inventions.

The present improved mold making machine is designed to combine in one structure mechanism both for jolting or jarring the 15 mold box in order to pack the sand around the pattern, and for inverting said mold box and pattern and withdrawing the latter from the sand. The general type to which the machine belongs is that known as the 20 roll-over type, in which the mold is turned over about a substantially central axis instead of being oscillated about an axis to its one side, as in the rock-over type of machine. In addition to thus combining jolting, in- 25 verting and drawing means in one machine, the present improvements include means for easily removing a mold from under the roll-over table, as also various details of improvement connected with the foregoing features, 30 all of which will be hereinafter fully described and particularly pointed out in the claims.

The annexed drawings and the following description set forth in detail certain mechanism embodying the invention, such dis- 35 closed means constituting, however, but one of various mechanical forms in which the principle of the invention may be used.

In said annexed drawings:—

40 Figure 1 is a plan view of a mold making machine embodying my present improvements; Fig. 2 is a side elevational view of the same; Fig. 3 is an end elevation thereof; Fig. 4 is a side elevation similar to Fig. 2, 45 but with certain parts broken away, and other parts shown in a different operative position; Fig. 5 is a part sectional and part elevational view of a detail of construction; Fig. 6 is a sectional view of such detail at 50 right angles to the plane of Fig. 5, as indicated by the line 6—6, in said figure; Fig. 7 is a sectional view of another detail as indicated by the line 7—7, Fig. 2; Fig. 8 is a vertical section taken on the line 8—8, Fig. 3,

and showing the jarring mechanism proper; Fig. 9 is a horizontal section of the truck for removing the molds, the plane of the section being indicated by line 9—9, Fig. 2; Fig. 10 is a vertical section of such truck as indicated by the line 10—10, Fig. 1; and Figs. 11 55 and 12 are respectively a side elevation and a front elevation of a modified construction of the machine.

As indicated by the sectioning in Figs. 1 to 4 inclusive, the machine in hand is de- 60 signed to be set in a pit 1, or at least below the floor line 2 on which the operators work, so that the roll-over table pattern-plate carrier 3 in its lower position will be located only a short distance above the floor line, 70 thus bringing a flask 4, when the same is se- 65 cured thereon, in conveniently accessible position for filling with sand and for doing such tamping as may be found necessary. This roll-over table 3, which forms the cen- 75 tral operative element of the machine is, along with the various other operative parts, supported on two end-frames or standards 5, one at each end that are in turn firmly se- 80 cured to a bed-plate 6. On the latter is also 85 centrally mounted a jarring cylinder 7, as will be presently more fully described. The end frames 5 are additionally supported by transverse bars 8 extending from either side of such jarring cylinder, as shown in Fig. 3. 35

The detailed construction of the jarring cylinder is not of interest in this connection, being not presented as a part of the present invention. It will suffice, accordingly, to note in Fig. 8 that a piston 9, reciprocable in 90 said jarring cylinder, supports a platform or head 10 of general rectangular form sub-stantially filling the space between the two side standards 5. This piston is adapted to be alternately raised and then allowed to fall of its own weight by admitting air under pressure beneath the piston and then exhaust- 95 ing such air in rapid succession, an automatically operating valve 11 being adapted to control such admission and exhaust, as need not be further explained. The piston, upon dropping, contacts with a reinforced portion 12 of the bed 6 which forms an anvil and thus shocks or jolts anything resting 100 upon the platform or top.

In the normal position of parts illustrated in Figs. 1, 2 and 3 the roll-over table 3 thus rests on the jarring platform 10, said table 105

being designed when in this position to receive the mold-box or flask 4 and to have the latter filled with sand, said platform and table being jarred, as occasion requires, 5 to pack the sand around the pattern plate which is directly secured to the face of the roll-over table. For operative purposes other than such jarring, the table is supported by means of trunnions 13 (see Figs. 10 2 and 6) extending in opposite directions from side plates 14 forming part of the table structure, so as to lie in recesses 15 formed in the upper ends 16 of two plungers 17 vertically reciprocable in guides 18 formed in 15 the respective end standards 5. The recesses 15 are in effect vertically extending slots of a length sufficient to permit the free up and down movement of the table in the jarring operation just referred to, without the trunnions 20 contacting with either end of the recess. Upon the plungers, however, being raised, the trunnions are engaged by the bottoms of the recesses and the table thus lifted bodily to an elevation sufficient to permit 25 of the rolling over thereof in order to invert the pattern and attached flask or mold-box.

Actuation of the plungers 17 to thus elevate the roll-over table is secured from a 30 rock shaft 19 extending transversely of the machine in front of the jarring cylinder 7 and provided with two arms 20, one at each end, that are respectively connected by links 21 with the adjacent plungers. Rock shaft 35 19 is in turn connected by means of another lever arm 22 with the piston rod 23 of a power cylinder 24 that is oscillatorily supported in trunnion bearings 25 alongside and slightly to the rear of the machine at 40 the bottom of the pit 1 in which the latter is located. The piston in said cylinder is conveniently actuated by means of compressed air, where the latter is utilized for operating the jolting mechanism, a single 45 valve 26 being arranged in the air-line 27 so as to control the supply of air to the cylinder of the jolting mechanism through a pipe 28 and to the cylinder 24 through a flexible connection 29.

50 Extending parallel with the piston rod 23 is another rod 30 fixed to the forward end of the cylinder and having on its outer end an adjustable nut 31 forming a stop, with a second nut 32 for locking it in desired position on the rod. This fixed rod 30 engages a lug 33 depending downwardly from the lever arm and adapted to engage such stop. The adjustment of the stop on the rod is designed to be such that when the rollover 55 table, with the mold-box attached thereto, is inverted and lowered, said lug will engage the stop and hold the parts in question in suspension, as it were.

This is to permit the utilization of a leveling 60 table of the kind described in United

States Letters Patent Reissue No. 13,097, to receive the mold when released from the roll-over table. Such leveling table in the present instance is in the form of a car or truck 34 movable along two parallel rails 35 disposed substantially on the level of the floor 2 and extending between and beyond the end standards 5 of the machine, so as not to interfere with the operations heretofore described and yet permit of the positioning of the car directly under the roll-over table, when the latter is raised and inverted. Such car supports a series of depressible members 36 (shown as four in number in Figs. 9 and 10, *q. v.*), which are 70 normally held in raised position by springs 37, so that when the bottom board of the mold comes in contact therewith, upon lowering the roll-over table, said members may be depressed more or less to conform with 75 inequalities in such bottom board, the adjustment of the stop 31 on the rod preventing the complete compression of the springs under the members 36. Thereupon the members are locked by a lever 38 which forces 80 two U-shaped bars 39 outwardly through the medium of a double cam 40 connected with the inner end of said lever, the outer ends of said bars frictionally engaging the respective depressible members. When the members are thus locked, the mold-box may be 85 detached from the roll-over table, without fear of any yielding or settling which might otherwise damage the mold.

The rolling over of the table 3 is designed 90 to be automatically effected incidentally to the raising of the latter by means of the rock-shaft 19 and its connections, as previously set forth. For this purpose a sheave 41 is formed integrally with each end 14 of 95 the table concentric with the trunnions 13, whereby said table is adapted to be supported on the plungers. Attached at one end to each such sheave is a cable shown as a chain 42 which in the normal position of 100 the machine is wrapped partially around the sheave, as shown in Fig. 5, the other end of said chain being connected to a vertically disposed rod 43 passing through a recess or 105 aperture 44 in the adjacent end frame 5 of the machine. A nut 45 on the lower end of said rod forms a stop which is adapted to limit the upward movement of the rod while still leaving the same free to move downwardly. A compression spring 46 interposed 110 between the nut and the frame serves to cushion the engagement of the former with the latter upon the upward movement just referred to.

With the parts in the position illustrated 115 in Figs. 1 and 5, it will be obvious that any upward movement of the plungers 17 will serve to rotate the sheaves 41 and thereby the table, owing to the forced unwinding of the chain, the lower end of which is held 120

against movement by reason of the engagement of the stop 45 on the rod 43 with the frame.

The table is shown in completely rolled over position in full lines in Fig. 4, and is adapted to be locked in this position by means of a locking pin 47 carried in an arm 48 projecting forwardly from the respective upper ends 16 of the plungers. As shown in Fig. 7 this locking pin is normally disposed inwardly by a compression spring 49, but may be drawn outwardly by a hand-wheel 50 threaded thereon to bring its beveled head into engagement with a complementary recess 51 in the adjacent end portion 14 of the table.

With the table thus locked, the plungers may be lowered, while still maintaining the table in its rolled over position, such lowering movement continuing until the lug 33 on the lever arm 22 contacts with the stop 31, as already explained. After the table has thus been lowered and the mold box detached therefrom, the table is raised and the pattern withdrawn from the mold by raising the plungers 17 a second time, leaving the mold behind on the car 34, ready to be drawn back from the machine on the track.

To return the table to its initial position it is next necessary to unlock the pin 47 by rotating the hand-wheel 50 in the opposite direction to that previously described; then by lowering the plungers 17, giving a slight initial push to the table, the latter will swing around its trunnion axis and resume its normal position, as shown in Fig. 1, by the time the plungers are completely lowered.

The complete cycle of operations of the machine may now be briefly reviewed. With the parts in their normal position as shown in Fig. 2, for example, the mold-box or flask 4 is placed on the roll-over table 3 and sand filled therein around the pattern, which latter is securely attached to the face of the table. As the filling proceeds the table is jarred one or more times by admitting air to the jarring cylinder through valve 26 and pipe 28, so as to pack the sand properly. When the mold box is finally full, the bottom board 4^a is placed in position and, together with the box, clamped to the table, (see Fig. 3). The plungers 17 are now raised by the admission of air to the actuating cylinder 24 through pipe 29, the result of this operation being not only to elevate the table, but to roll the same over so that it occupies the position shown in full lines in Fig. 4. The car 34 carrying the leveling table is moved along the rails 35 into position directly underneath the inverted mold box, which is thereupon lowered by exhausting the air from the actuating cylinder 24 until the bottom board of the mold box is brought into contact with the depressible members 36 on such car. After locking these members,

the clamping devices that secure the mold to the table are loosened and the table again raised, thereby withdrawing the pattern from the molded sand in the mold box, and leaving the latter free to be moved with the truck to the other end of the rails. The table is now again in the position shown in full lines in Fig. 4, and the next step is to lower the same back to its normal position. To this end the locking pin 47 is withdrawn from engagement and the table given a slight push as the plungers are allowed to descend, whereupon the further downward movement of the table causes it to roll back on its trunnions to its lower position, ready to receive another flask or mold box.

The modification in construction illustrated in Figs. 11 and 12 consists principally in the utilization of two plungers 52 at each end of the frame instead of just one (17) as already described. This is desirable where unusually heavy loads are to be handled, and even in the smaller sizes of the machine it obviously insures steadiness and accuracy in the movement of the roll-over table, this being particularly desirable when the table is raised to withdraw the pattern. To operate said two pairs of plungers, two rock shafts 53 are employed, being connected with the respective plungers by means of arms 20 and links 21 just as in the case of the single rock shaft and single pair of plungers of the first described form of the machine. Each of these rock shafts, however, carries an additional arm 54 and said arms are connected by means of a link 55, whereby movement of the one is imparted to the other in equal degree. For the purpose of rocking the shafts a power cylinder 56 is utilized similar to the one previously described, except that it is disposed inside instead of outside of the frame structure of the machine, being connected with the forward rock shaft by means of an arm fixed on said shaft and pivotally attached to the outer end of the piston rod 23. The arrangement of the other parts is substantially identical with the previous construction, and the same reference letters have been applied to such parts.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In mechanism of the character described, the combination of a jarring platform; vertically reciprocable members adjacent to said platform; a roll-over pattern-plate carrier adapted in normal position to rest on said platform out of engagement

with said members, said carrier having trunnions adapted to be engaged by said members when the latter are raised or when said carrier is in its inverted position; and means adapted to lock said carrier, when in inverted position, to one of said members, said means comprising a locking pin reciprocably mounted in said member and means for reciprocating the same.

2. In mechanism of the character described, the combination of a jarring platform; vertically reciprocable members adjacent to said platform; a roll-over pattern-plate carrier adapted in normal position to rest on said platform out of engagement with said members, said carrier having trunnions adapted to be engaged by said members when the latter are raised or when said carrier is in its inverted position; and means adapted to lock said carrier, when in inverted position, to one of said members, said means comprising a locking pin reciprocably mounted in said member, a spring tending to move said pin out of locking position, and a hand-wheel threaded on said pin and adapted to draw the same into such position.

3. In mechanism of the character described, the combination of a jarring platform; a pattern-plate carrier normally resting on said platform; vertically reciprocable members adjacent to said platform, said members being normally out of engagement with said carrier but adapted to raise the same clear of said platform; and a leveling table movable into and out of position between said platform and carrier in the raised position of the latter.

4. In mechanism of the character described, the combination of a jarring platform; a pattern-plate carrier normally resting on said platform; vertically reciprocable members adjacent to said platform, said members being normally out of engagement with said carrier but adapted to raise the same clear of said platform; a track extending transversely of said platform; and a truck provided with a leveling table and adapted to run on said track into and out of position between said platform and carrier in the raised position of the latter.

5. In mechanism of the character described, the combination of a jarring platform; a pattern-plate carrier normally resting on said platform; vertically reciprocable members adjacent to said platform, said members being normally out of engagement with said carrier but adapted to raise the same clear of said platform; a leveling table movable into and out of position between said platform and carrier in the raised position of the latter; and power means connected to simultaneously reciprocate said members.

6. In mechanism of the character de-

scribed, the combination of a jarring platform; a pattern-plate carrier normally resting on said platform; vertically reciprocable members adjacent to said platform, said members being normally out of engagement 70 with said carrier but adapted to raise the same clear of said platform; a track extending transversely of said platform; a truck provided with a leveling table and adapted to run on said track into and out of position 75 between said platform and carrier in the raised position of the latter; a rock-shaft disposed transversely of said members and operatively connected therewith; and a power cylinder and piston connected to rock 80 said shaft.

7. In mechanism of the character described, the combination of a jarring platform; a pattern-plate carrier normally resting on said platform; vertically reciprocable 85 members adjacent to said platform, said members being normally out of engagement with said carrier but adapted to raise the same clear of said platform; a leveling table movable into and out of position between 90 said platform and carrier in the raised position of the latter; and means, independent of said platform, adapted to limit the downward movement of said carrier when in inverted position.

8. In mechanism of the character described, the combination of a jarring platform; a pattern-plate carrier normally resting on said platform; vertically reciprocable 100 members adjacent to said platform, said members being normally out of engagement with said carrier but adapted to raise the same clear of said platform; a leveling table movable into and out of position between 105 said platform and carrier in the raised position of the latter; and an adjustable stop adapted to limit the downward movement of said carrier when in inverted position.

9. In mechanism of the character described, the combination of a jarring platform; a pattern-plate carrier normally resting on said platform; vertically reciprocable 110 members adjacent to said platform, said members being normally out of engagement 115 with said carrier but adapted to raise the same clear of said platform; a leveling table movable into and out of position between said platform and carrier in the raised position of the latter; power means connected 120 to simultaneously reciprocate said members; and a stop adapted to limit the downward movement of said members, whereby said carrier may be suspended over said leveling table, substantially as described.

10. In mechanism of the character described, the combination of a jarring platform; a pattern-plate carrier normally resting on said platform; vertically reciprocable 125 members adjacent to said platform, said 130

members being normally out of engagement with said carrier but adapted to raise the same clear of said platform; a track extending transversely of said platform; a truck 5 provided with a leveling table and adapted to run on said track into and out of position between said platform and carrier in the raised position of the latter; a rock-shaft disposed transversely of said members and 10 operatively connected therewith; a power cylinder and piston connected to rock said shaft; and an adjustable stop co-operative with said piston to limit the downward movement of said members, whereby said 15 carrier may be suspended over said leveling table, substantially as described.

11. In mechanism of the character described, the combination of a suitable base, a fluid pressure jarring platform mounted 20 thereon; standards laterally adjacent to said platform; plungers vertically reciprocable in said standards; a transversely disposed rock-shaft journaled in said standards and operatively connected with said plungers; a 25 power cylinder disposed alongside said base; a piston reciprocable in said cylinder and connected to rock said shaft; and fluid pressure supply connections for said jarring platform and said power cylinder, respectively. 30

12. In mechanism of the character described, the combination of a suitable base, a fluid pressure jarring platform mounted thereon; standards laterally adjacent to said 35 platform; plungers vertically reciprocable in said standards; a transversely disposed rock-shaft journaled in said standards and operatively connected with said plungers; a power cylinder disposed alongside said base; 40 trunnion bearings supporting said cylinder; a piston reciprocable in said cylinder and connected to rock said shaft; a rod projecting from said cylinder; a stop carried by said rod and adapted to limit the rocking 45 of said shaft in one direction; and fluid pressure supply connections for said jarring platform and said power cylinder, respectively.

13. In combination, a molding machine 50 including a table and a flask-carrying support vertically movable with respect to said table, and a self-equalizing flask carrier movable onto and away from said table and including a body portion, flask-carrying 55 portions mounted on said body portion so as to be movable to conform with the flask, and means carried by said body portion for locking said flask-carrying portions in their moved position.

14. In combination, a molding machine 60 including a table and a flask-carrying support vertically movable with respect to said table, tracks in co-operative relation with said table, and a self-equalizing flask carrier 65 movable on said tracks onto and away from

said table, said flask-carrier including a body portion, flask-carrying portions mounted on said body portion so as to be movable to conform with the flask, and means carried by said body portion for locking said flask-carrying portions in their moved position. 70

15. In mechanism of the character described, the combination of a platform; a roll-over pattern-plate carrier adapted in normal position to rest on said platform; 75 vertically reciprocable members adjacent to said platform, adapted to raise said carrier clear thereof in order to permit the same to be rolled over; and means limiting the downward movement of said members to a 80 position wherein they will support said carrier, when thus inverted, with mold-box entirely clear of said platform.

16. In mechanism of the character described, the combination of a platform; a 85 roll-over pattern-plate carrier adapted in normal position to rest on said platform; vertically reciprocable members adjacent to said platform, adapted to raise said carrier clear thereof in order to permit the same to 90 be rolled over; and adjustable means limiting the downward movement of said members to a position wherein they will support said carrier, when thus inverted, with mold-box entirely clear of said platform. 95

17. In mechanism of the character described, the combination of a platform; a roll-over pattern-plate carrier adapted in normal position to rest on said platform; 100 vertically reciprocable members adjacent to said platform, adapted to raise said carrier clear thereof in order to permit the same to be rolled over; power means adapted to reciprocate said members; and means independent of said power means positively 105 limiting the downward movement of said members to a position wherein they will support said carrier, when thus inverted, entirely clear of said platform.

18. In mechanism of the character described, the combination of a platform; a roll-over pattern-plate carrier adapted in normal position to rest on said platform; 110 vertically reciprocable members adjacent to said platform, adapted to raise said carrier clear thereof in order to permit the same to be rolled over; power means adapted to reciprocate said members, and adjustable means independent of said power means positively 115 limiting the downward movement of said members to a position wherein they will support said carrier, when thus inverted, entirely clear of said platform. 120

19. In mechanism of the character described, the combination of a platform; a roll-over pattern-plate carrier adapted in normal position to rest on said platform; 125 vertically reciprocable members adjacent to said platform, adapted to raise said car- 130

rier clear thereof in order to permit the same to be rolled over; a leveling table movable into and out of position between said platform and carrier in the raised position 5 of the latter; and means limiting the downward movement of said members to a position wherein they will support said carrier when thus inverted, with mold-box in proper coöperative relation with said leveling table.

20. In mechanism of the character described, the combination of a platform; a roll-over pattern-plate carrier adapted in normal position to rest on said platform; 15 vertically reciprocable members adjacent to said platform, adapted to raise said carrier clear thereof in order to permit the same to be rolled over; a leveling table movable into and out of position between said 20 platform and carrier in the raised position of the latter; and adjustable means limiting the downward movement of said members to a position wherein they will support said carrier when thus inverted, with mold-box 25 in proper coöperative relation with said leveling table.

21. In mechanism of the character described, the combination of a platform; a roll-over pattern-plate carrier adapted in 30 normal position to rest on said platform; vertically reciprocable members adjacent to said platform, adapted to raise said carrier clear thereof in order to permit the same to be rolled over; a leveling table movable into and out of position between said 35 platform and carrier in the raised position of the latter; power means adapted to reciprocate said members; and means independent of said power means positively 40 limiting the downward movement of said members to a position wherein they will support said carrier when thus inverted, with mold-box in proper coöperative relation with said leveling table.

22. In mechanism of the character described, the combination of a platform; a roll-over pattern-plate carrier adapted in normal position to rest on said platform;

vertically reciprocable members adjacent to said platform, adapted to raise said carrier clear thereof in order to permit the same to be rolled over; a leveling table movable into and out of position between said platform and carrier in the raised position of the latter; power means adapted to reciprocate said members; and adjustable means independent of said power means positively limiting the downward movement of said members to a position wherein they will support said carrier when thus inverted, with mold-box in proper coöperative relation with said leveling table.

23. In mechanism of the character described, the combination of a jarring platform; a roll-over pattern-plate carrier adapted in normal position to rest on said platform; vertically reciprocable members adjacent to said platform, said members being normally out of engagement with said carrier, but adapted to raise the same clear 70 of said platform to be rolled over; and means limiting the downward movement of said members to a position wherein they will support said carrier, when thus inverted, with mold-box entirely clear of said 75 platform.

24. In mechanism of the character described, the combination of a jarring platform; a roll-over pattern-plate carrier adapted in normal position to rest on said 80 platform; vertically reciprocable members adjacent to said platform, said members being normally out of engagement with said carrier, but adapted to raise the same clear 85 of said platform to be rolled over; and adjustable means limiting the downward movement of said members to a position wherein they will support said carrier, when thus inverted, with mold-box entirely clear 90 of said platform.

Signed by me, this 11 day of Nov., 1913.

EDWIN S. CARMAN.
